UNITED STATES PATENT OFFICE.

HENRY HEINEMANN, OF ST. LOUIS COUNTY, MISSOURI.

SULKY.

SPECIFICATION forming part of Letters Patent No. 399,231, dated March 5, 1889.

Application filed November 22, 1888. Serial No. 281,563. (No model.)

To all whom it may concern:

Be it known that I, HENRY HEINEMANN, a citizen of the United States, residing in the county of St. Louis and State of Missouri, have 5 invented certain new and useful Improvements in Sulkies, of which the following is such a full, clear, and exact description as will enable any one skilled in the art to which it app pertains to make and use the same, reference 10 being had to the accompanying drawings, forming part of this specification.

The object of my invention is to construct a sulky in which the horse can be brought much nearer to the axle and driver than heretofore.

The invention lies in the simplicity of the construction, and principally in the novel form of spring-supporting devices for the seat, and also lies in certain combinations of parts, 20 which will be hereinafter described in detail and pointed out in the claims, making a part hereof.

Figure 1 represents a plan view of a sulky made in accordance with my invention. Fig. 25 2 is a rear elevation thereof, and Fig. 3 is a view of a detail on an enlarged scale.

The same figures of reference indicate the same parts throughout the several views.

4 4 are the shafts, which are secured in any well-known way to an axle, 5, which axle 5 may be bowed, as shown in Fig. 2.

6 is a cross-piece which joins the two shafts together, and 7 is a curved bar which is attached at its center to the cross-piece 6, and 30 is secured at its outer ends to the shafts, as ordinarily.

8 is a seat which is supported through the instrumentality of four connecting-rods, 9, by 40 means of springs 10, to which the connecting-rods 9 are pivotally joined. The connecting-rods 9 are joined to the seat 8 in any well-known manner. Two of these rods 9 are on each side of the seat, and they are arranged at each side of the axle. The springs 10, 45 Fig. 3, are made out of wire or stout bars of metal, which are coiled, so as to leave the ends free and a middle part, 11, projecting.

12 is a plate having ears 13 13 projecting therefrom. The middle portion, 11, of the 50 springs 10 is adapted to rest on the plate 12, and the two are firmly held in place by the

same clips, 14 14, that secure the shafts to the axle. One turn of each of the coils of the springs 10 passes around the ears 13 13, and thereby support and hold said springs in position. To keep the seat from moving back and forth braces 15 15 are provided. These braces are secured to eyebolts 16 16, which pass through the shafts and are secured to the seat 8 in any well-known manner.

60 17 is the foot-crate, which supports the feet of the driver. It is hung by means of curved rods 18 18, having hook-shaped ends from preferably the cross-piece 6 and the back of the seat by means of eyebolts 19 19 on the cross-piece 6 and screw-eyes 20 20 beneath the back part of the seat. This allows the foot-crate 17 to be unhooked and removed when desired.

70 By the employment of the supporting devices described I am enabled to curve the axle 5 upward, so as not to interfere with the horse's hind feet. This permits me to hitch the horse much closer than in any sulky now used, so that the horse can be brought nearer 75 to the driver and axle. If necessary, the crate 17 can be removed when speeding horses, so that they can be hitched closer still and the sulky will not interfere with their action, as this will allow more space for the horse's 80 hind feet.

Sulkies as now constructed have spring-supporting devices for sustaining the seat, which spring-supporting devices preclude the axle from being bowed to any great extent to 85 accommodate the horse's hind feet. My invention secures this advantage in a marked and simple manner.

Having now set forth my invention, what I desire to claim and secure by Letters Patent 90 of the United States as my invention is—

1. A sulky having a curved axle, and having the seat thereof supported from said axle by means of coil-springs and connecting-rods arranged at each side of said seat and axle.

95 2. As a means for supporting the seat of a sulky, coil-springs secured to the axle of said sulky at each side of said seat, having the ends thereof arranged on each side of the axle and connected to said seat.

100 3. A spring-supporting means for a sulky embodying, essentially, connecting-rods 9, se-

cured to the seat of the sulky, arranged at each side of said seat and at each side of the axle, and coil-springs 10, secured to said axle and having the free ends pivotally fastened 5 to said connecting-rods.

4. The combination, in a sulky, of a seat, as 8, connecting-rods 9 at each side of said seat, supporting the same through the instrumentality of coil-springs 10, secured to the axle of 10 the sulky, the said connecting-rods and ends of the coil-springs being arranged on each side of said axle, and ears 13, extending from said axle and supporting the coils of the springs 10.

5. The combination, in a sulky, of the curved 15 axle 5, a seat, as 8, supported by said axle through the instrumentality of connecting-

rods 9 at each side of said seat and axle, coil-springs 10, secured to said axle, having their ends pivotally secured to said connecting-rods, plates 12, having ears 13 13 for supporting the coils of the springs 10, and braces 15 20 15, secured to said seat and to the shafts of said axle, for the purpose described.

In testimony whereof I have hereunto set my hand and affixed my seal, this 20th day of 25 November, 1888, in the presence of two subscribing witnesses.

HENRY HEINEMANN. [L. S.]
